UNITED STATES PATENT OFFICE

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS

FUEL CONTROL MEANS FOR A HYDROCARBON BURNER

Application filed May 14, 1927. Serial No. 191,296.

My invention relates to a fuel control means for a hydrocarbon burner and has for particular purpose the provision of means for controlling the flow of a liquid hydrocarbon fuel. Another purpose is the provision of a thermostatically controlled fuel regulation. Another purpose is the provision of a thermostatic control, with means for cutting off the supply of fuel when the temperature rises above a predetermined point, and for supplementally increasing the normal supply of fuel when the temperature drops below a predetermined point. Another object is the provision of an improved overflow control. Other objects will appear from time to time in the course of the specification and claims.

I illustrate my invention more or less diagrammatically in the accompanying drawings, wherein—

20 Figure 1 is a vertical section of my device with parts in elevation and with the electric circuits diagrammatically shown;

Figure 2 is a plan view of the control device proper, with the cover removed;

25 Figure 3 is a section on the line 3—3 of Figure 2;

Figure 4 is a section on the line 4—4 of Figure 2;

Figure 5 is a section on the line 5—5 of 30 Figure 3; and

Figure 6 is a section on the line 6—6 of Figure 3.

Like parts are indicated by like symbols throughout the specification and drawings.

35 A generally indicates the outer shell or drum of a hydrocarbon burner, A¹ being the upper or combustion chamber. A² is a transverse partition centrally apertured as at A³. Seated in the aperture A³ is the mixing drum or chamber A⁴ with the concave bottom A⁵. The drum is provided with a plurality of small apertures A⁶ spaced in general uniformity about the intermediate and lower portion of its walls. Adjacent the upper edge of the 40 walls is a row A⁷ of larger and upwardly in-

clined apertures. A⁸ is an upwardly and inwardly inclined flange projecting inwardly from the upper edge of the drum A⁴. A⁹ is a distributor member in the center of the bottom member A⁶ and A¹⁰ are apertures in 50 the walls thereof. A¹¹ indicate air inlet apertures about the lower edge of the drum A and A¹² are any suitable air inlets whereby air may pass through the transverse partition A¹⁴ which underlies the mixing chamber A⁴. 55

B indicates an oil supply line which extends from any suitable oil supply to the float chamber generally indicated as C. B¹ is an oil line extending from said float chamber and communicating, by the elbow B² with the 60 bottom A⁵ of the mixing chamber A⁴. B³ is a gas line which extends into the union member B⁴ and axially along the pipe B¹ to terminate as at B⁵ within the distributor member A⁹ in the mixing chamber at a level above 65 the normal level of admittance of the liquid fuel. B⁶ is a bushing member adapted to receive the fuel line B¹. It may be secured in relation to the burner for example by the set screw B⁷ in the hollow member B⁸ which is 70 secured as at B⁹ to the drum A.

Referring more particularly to the flow chamber, as shown in Figures 2 and following the fuel line B communicates with the initial admission chamber C¹ in which is positioned the strainer C² yieldingly thrust upwardly by the spring C³ against an upper abutment C⁴. C⁵ is a removable screw threaded plug which engages the spring C³ and which permits removal of the strainer 80 and access to the chamber C¹. C⁶ is a fuel passage extending upwardly from said chamber and controlled by the valve member D. This valve member is pivoted to the end of a lever D¹ which lever is in turn pivoted as at 85 D² closely adjacent its connection with the valve member D. Its opposite end is downwardly turned as at D³ and is secured to the float D⁴. It will be understood that when the 90 level of oil in the float chamber is below the

predetermined normal oil flows through the passage B and the passage C⁶ and escapes over the ledge C⁷ to the float chamber proper indicated as C⁸. D⁵ is a shield, associated with the valve D, and adapted to prevent any substantial upward gush of the inflowing fuel.

As shown in Figure 5 the ledge C⁷ is bounded at one end by a raised portion C¹⁰ through which extends the outlet or over-flow passage C¹¹.

E indicates a transverse rod upon which is pivoted the weight E¹. Preferably formed integrally with such weight is the lever E² to the end of which is pivoted a stem E³ extending downwardly through the passage C¹¹. It terminates at its lower end in the hook E⁴ to which may be secured the bail E⁵ of the overflow control bucket E⁶. E⁷ is a laterally projecting lug herein shown as associated with the lever E², and E⁸ is a corresponding lateral projection mounted upon the lever E⁹ at the opposite side of the rod E. It will be understood that in case the float chamber becomes so filled that oil flows downwardly through the over-flow passage C¹¹ and fills the bucket, the weight of the bucket will trip the counterweight E¹ and will cause it to take the position shown in dotted line in Figure 3. In such case the projection E⁸ will contact the lever D¹ and rotate it about its pivot D² in such wise as to close the valve D and prevent further admission of fuel. On the other hand, if the trip bucket E⁶ is removed from the hook E⁴ the counterweight E¹ will drop to the position shown in dotted line in Figure 4. In such case the lug E⁷ will contact the lever D¹ and close the valve D. Thus no fuel can flow into the float chamber unless the over-flow bucket is in position, and no fuel can flow into the chamber when the over-flow bucket is sufficiently full to tilt the weight E¹ to the right of the position in which it is shown in full line in Figures 3 and 4. When the over-flow bucket E⁶ is in position, and is not so filled, it is normally held, by the weight E¹, in the full line position shown, being drawn up against the bottom of the float chamber.

The weight E¹ is kept in proper position in relation to the lever D, for example by the spacing sleeves E¹⁰ E¹¹ on the pin E. E¹² is a semi-circular guard to protect the overflow bucket E⁶.

The fuel line B¹ is connected with a downward projection or boss G positioned on the side of the float chamber opposite to the inlet chamber C¹. It is provided with an aperture G¹ in opposition to the end of the line B¹, access to which may be had by removal of the square ended screw G², as shown in Figure 3. In communication with the space G¹ are two ducts G³ G⁴ which in turn communicate with the vertical apertures G⁵ G⁶. Screw threaded in these apertures are the valve cyl-

inders G⁷ in the lower ends of which are screw threaded the valve seats G⁸. G⁹ G¹⁰ are valve stems slideable in the bearing members G¹¹ which are screw threaded into the upper ends of the sleeves G⁷. The upward movement of said stems is limited by a pin or stop G¹², adjustment of the valve excursion being obtainable by rotation of the screw threaded members G¹¹. The valve cylinders G⁷ are apertured as at G¹³ to receive the oil passing through the circular screen members G¹⁴ which are held in position by tension springs G¹⁵, one end being frictionally engaged by the threaded members G¹¹. Each valve cylinder G⁷ is provided with an air hole G¹⁶ above the fuel level. G¹⁷ is an air vent member extending upwardly from the passage G¹ to the point well above the highest possible fuel level.

I prefer to render the valves G⁹ G¹⁰ responsive to temperature conditions. The thermostatic control may be based upon temperatures adjacent the burner or upon local or room temperatures taken elsewhere, depending upon the needs of the particular installation. Referring to the diagrammatic portion of Figure 1 H indicates the house current which may for example be a 110 volt current. H¹ is the primary coil of a transformer, in such house circuit and H² is a secondary coil of such transformer. H³ is a conductive line extending from one end of said secondary coil H² to the terminal H⁴. H⁵ is a conductive line extending from the opposite end of the secondary coil to any suitable thermostatic leaf H⁶. Opposed to such leaf are the contacts H⁷ and H⁸. When the temperature rises to a predetermined point the leaf H⁶ will touch one of said contacts, for example H⁷ and the six volt current will pass through such contact along the conductive line H⁵ to a terminal H¹⁰. On the contrary when the temperature drops to a predetermined degree a circuit will be closed through the opposite contact H⁸ and the six volt current will pass along the conductive line H¹¹ to the terminal H¹².

I, I¹ are generally similar bi-metallic thermostatic strips which are adapted to flex in opposite directions in response to similar changes in temperature. I² and I³ are resistance members or coils associated respectively with the leaves I and I¹.

The leaves are apertured at their outer ends as at I⁴ I⁵ to receive the upper ends of the valve stems G⁹ and G¹⁰. The cross pins G¹⁹ G²⁰ of said valve stems engage the upper surface of the thermostatic leaves.

It will be understood that when the leaf H⁶ deflects to the right, as shown in Figure 1, and closes the circuit through the contact H⁷ and conductor H⁵ the circuit is continued through the resistance I² by means of the conductive connection I⁶ from the terminal H¹⁰ to the resistance and the conductive connection I⁷

from the resistance to the return terminal H^4 . Similarly, if the leaf H^6 deflects in the opposite direction, in response to a drop in temperature, the circuit is closed through the line H^{11} and the terminal H^{12} and passes thence by the conductive line I^8 to the resistance I^3 and thence by the conductive line I^9 to the return terminal H^4 .

When the leaf H^6 is in intermediate position and neither resistance is actuated, the leaf I and the resistance I^2 will be in the position shown in dotted line at the right of Figure 6 and the valve stem G^{10} will be upwardly withdrawn to permit a flow of fuel through the aperture G^6 and the duct G^4 into the fuel line B^1 . As long as the temperature remains within the predetermined range, fuel will be supplied to the fuel line B^1 through but a single duct. However when the temperature exceeds the predetermined normal and the resistance I^2 is heated, the leaf I flexes to the position shown in full line at the right of Figure 6 and the valve G^{10} is permitted to drop into closed position.

If the temperature drops below the desired normal range, the resistance I^2 is of course not heated and the valve stem G^{10} remains in open position. But the resistance I^3 becomes heated and the leaf I^1 flexes upwardly into the position shown in dotted line in Figure 6. This flexure of the leaf causes it to lift the valve stem G^9 , thus permitting fuel to flow to the line B^1 through the duct G^3 . The valve unit is protected by a cover K fastened to the float chamber C by screws K^1 .

It will be realized that whereas I have shown and described a practical and operative device, nevertheless many changes might be made in the size, shape, number and disposition of parts without departing from the spirit of my invention. I therefore wish my description and drawings to be taken as in a broad sense diagrammatic and illustrative rather than as limiting me to my specific showing.

I claim:

1. In a fuel control device for a hydrocarbon burner, a fuel chamber, a fuel line to said chamber, a fuel line extending from said chamber to the burner, a plurality of ducts between said chamber and said last mentioned fuel line, valve members adapted to control said ducts, thermostatic members adapted to actuate said valve members, resistance members associated therewith, and actuating circuits therefor, and means responsive to temperature changes, for closing said circuits.

2. In a fuel control device for a hydrocarbon burner, a fuel chamber, a fuel line to said chamber, a plurality of ducts between said chamber and said last mentioned fuel line, valve members adapted to control said ducts, thermostatic members adapted to actuate said valve members, resistance members

associated therewith, and actuating circuits therefor, and means responsive to temperature changes, for closing one of said circuits in response to a predetermined rise in temperature, and for closing another of said circuits in response to a predetermined drop in temperature.

3. In a fuel control device for a hydrocarbon burner, a fuel chamber, a fuel line to said chamber, a fuel line extending from said chamber to the burner, a plurality of ducts between said chamber and said last mentioned fuel line, valve members adapted to control said ducts, a thermostatic member adapted to control each such valve, one of said valves being normally open, the thermostatic member therefor being adapted to close it upon a predetermined rise in temperature, and another valve being normally closed, the thermostatic member therefor being adapted to open it upon a predetermined drop in temperature.

4. In control means for a liquid fuel a float chamber, a fuel inlet, a plurality of outlet ducts, and valves adapted to control each such duct, and means for independently operating said outlet valves in response to temperature variations, including a thermostatic leaf for each such valve, a resistance associated therewith, actuating circuits for such resistances, and temperature responsive means for selectively closing such circuits.

5. In control means for a liquid fuel a float chamber, a fuel inlet, a plurality of outlet ducts, and valves adapted to control each such duct, means for independently operating said outlet valves in response to temperature variations, including a thermostatic leaf for each such valve, a resistance associated therewith, actuating circuits for such resistances, and temperature responsive means for selectively closing such circuits, one of said leaves being adapted to hold its valve normally open, and to close it in response to a predetermined temperature rise, the other being adapted to open a normally closed valve in response to a predetermined temperature drop.

6. In a fuel supply and control device for a hydrocarbon burner, a fuel chamber, a fuel line in communication with the chamber, extending to the burner, a plurality of inlet ducts interposed between said chamber and said fuel line, valves controlling said ducts and thermostatic control means for said valves, said thermostatic control means including thermostatic strips, resistance elements associated therewith and means for passing a current through said resistance elements in response to changes in temperature, the circuit for one of said resistance elements being adapted to be closed in response to decreases in temperature and the circuit of the other being adapted to be closed in response to increases in temperature.

7. In a fuel supply and control device for a hydrocarbon burner, a float chamber, a fuel inlet to said float chamber, a plurality of fuel outlets from said float chamber and 5 valves therefor, control members for said valves and thermostatic control means therefor including a thermostatic conductive strip responsive to adjacent temperature, contacts adapted to be opposed to said strip at the 10 opposite termini of its movement in response to fluctuations of temperature, a plurality of circuits, each such circuit adapted to actuate one of said members and including one of said terminals, and an electric connection 15 whereby each such circuit is closed and such control member is operated when the thermostatic conductive strip engages the contact with which such circuit is associated.

8. In a fuel supply and control device for a 20 hydrocarbon burner, a float chamber, means for delivering a liquid hydrocarbon fuel thereto, a fuel outflow line in communication with the chamber, extending to the burner, an outlet duct interposed between said float 25 chamber and said fuel line, a valve adapted to control said duct, and thermostatic control means for said valve, said thermostatic control means including a thermostatic strip within the float chamber, a resistance element 30 associated therewith, and means for passing a current through said resistance element in response to changes in temperature, said strip being mounted at one end upon the float chamber structure, the body and other end of the 35 strip being free to flex, and an actuating connection between the free end of the strip and said valve.

9. In a fuel control device for a hydrocarbon burner, a float chamber, a fuel line 40 tending to said chamber, a float in said float chamber, an inlet valve and control means interposed between said valve and said float adapted to actuate said valve in response to changes in level of said float, a fuel line 45 extending from said chamber to the burner, a plurality of outlet ducts extending from said float chamber to said fuel line, and differential means for controlling said ducts in response to temperature variations, said means 50 being adapted, at predetermined normal temperature, to maintain one of said ducts closed and one open.

10. The structure of claim 9 characterized by the provision of means adapted to open 55 the normally closed duct in response to predetermined temperature drops, and to close the normally open duct in response to predetermined temperature rises.

11. The structure of claim 9 characterized 60 in that a plurality of outlet ducts are provided with a separate valve for each, and a thermostatic control strip being provided for the actuation of each said valve, each such strip having associated therewith a resistance element, means being provided for

actuating said resistance elements in response to temperature conditions remote from the thermostatic strips.

12. In a fuel supply and control device for a hydrocarbon burner, a float chamber, a fuel inlet to said float chamber, a fuel line extending from said float chamber toward the burner, an outlet from said chamber to said fuel line, an air vent for the fuel line adjacent said outlet, a valve adapted to control said outlet, 75 and an air vent in communication with the float chamber side of the valve, said air vent extending to a level above the maximum level of the fuel in the float chamber. 75

13. In a fuel supply and control device for a hydrocarbon burner, a float chamber, a fuel inlet to said float chamber, a fuel line extending from said float chamber toward the burner, a plurality of outlets from said chamber to said fuel line, valves for said outlets, 80 and air vent means in communication with the float chamber side of each said valve, said air vent means extending to a level above the normal maximum level of the fuel in the float chamber. 85

14. In a fuel supply and control device for a hydrocarbon burner, a float chamber, a fuel inlet to said float chamber, a fuel line extending from said float chamber toward the burner, an outlet from said chamber to said fuel line, a valve for said outlet, an air vent for the outlet in communication with the float chamber side of the valve, and air vent means extending from said fuel line, adjacent said outlet, to a level above the normal maximum 90 level of the fuel in the float chamber. 95

15. In a fuel supply and control device for a hydrocarbon burner, a unitary float chamber housing, a float chamber, and a float 105 therein, a fuel inlet to said housing, a valve for said inlet, and means, responsive to said float for normally controlling said valve, a fuel line extending from said float chamber to said burner, an air vent for said fuel line, a valve seat for said fuel line, positioned within said float chamber member, a valve opposed thereto and means for controlling said valve, and a tubular member upwardly extending about said valve through said float chamber to a level above the normal maximum level of the fuel within said float chamber, said tubular member being apertured to permit the entry of fuel and being air vented, 110 above the fuel level. 115

16. In a fuel supply and control device, a 120 unitary housing member having a float chamber formed therein, a fuel inlet in communication with said housing member, said housing member having a strainer chamber in communication with said inlet, a strainer 125 within said chamber, a duct connecting said strainer chamber and said inlet, formed in a wall of said housing, a valve controlling said duct, a fuel line extending from said housing member to the burner, an air vent for said 130

fuel line, said housing wall being formed with a duct connecting said fuel line with the interior of the float chamber, a valve seat therefor, positioned within said housing member, and a valve adapted to control it, a tubular member surrounding said valve and extending upwardly through the float chamber, said tubular member surrounding said valve, said tubular member being vented at one level to permit the entry of fuel from the float chamber and being vented at a higher level to permit the escape of air from the space about said valve.

Signed at Chicago, county of Cook, and State of Illinois, this 11th day of May 1927.
